VISIBLE INDEX RECORD BOOK

John L. McMillan, Syracuse, N. Y., assignor to
McMillan Book Company, Syracuse, N. Y., a
corporation of New York

Application April 16, 1928. Serial No. 270,422

10 Claims. (Cl. 129—24)

This invention relates to a new and improved loose leaf binder of the type usually called a visible index record book and is particularly adapted for the type of loose leaf binders in which the sheets are retained on split rings.

In using loose leaf books of this type particularly where they are used to keep records of different accounts it is desirable to have the sheets in the book of such a size and so placed in the book that the title of each sheet will at all times be visible. In order to accomplish this result the sheets are usually less in width than the width of the binder itself so that they may be placed in the binder in overlapping relation leaving a portion of the top of each sheet exposed. In using this type of book it is frequently necessary to remove from the book from time to time sheets which represent an account which has been closed or sheets which it is desired to remove for some other reason. When this takes place it is usually the custom to place a new sheet in the book at the bottom thereof. It is then necessary to move the sheets adjacent the sheet which has been removed along the rings so that all of the sheets in the book will be uniformly spaced.

If the movement of the sheets along the rings can be accomplished without removing the sheets from the rings it is of a great advantage and permits the book to be used with much more ease and rapidity than would be the case if the sheets had to be removed bodily from the rings in order to change their position with reference to the rings.

It is also desirable to have a device by the use of which sheets may be moved in either direction and a distance of one or two rings as desired.

The main object of my invention is to provide a device which will permit the sheets in the book to be moved from one set of rings to another set of rings while retaining the sheets on rings at all times.

Another object of my invention is to provide a device which will permit the movement of the sheets either up or down in the book as desired and which will also permit such movement to be a distance of one or more rings as desired and attain this result in one operation.

Other objects and advantages relate to the size, shape and arrangement of parts all as will more fully appear from the following description taken in connection with the accompanying drawings in which:

Figure 1 is a top plan view of my device with the rings in closed position.

Figure 2 is a top plan view of my device with the rings in open position and with the ring carrying plates moved longitudinally with respect to each other.

Figure 3 is a section on line 3—3 of Figure 1.

Figure 4 is a section on line 4—4 of Figure 2.

Figure 5 is a section on line 5—5 of Figure 4.

Figure 6 is a section on line 6—6 of Figure 3. 65

Figure 7 is a section on line 7—7 of Figure 3.

In the drawings I have indicated two book covers —1— and —2— partially broken away and flexibly connected at their inner ends to a book back —3—. I provide a spring back plate 70

—4— secured to book back —3— by rivets —5— or other convenient means. Spring back plate —4— is return bent along each longitudinal edge to form troughs —6— and —7—. A toggle plate —8— has its outside longitudinal edge positioned in trough —6— and a companion toggle plate —9— has its outside longitudinal edge positioned in trough —7—. The inner longitudinal edges of toggle plates —8— and —9— are held in registration with each other by a plurality, in 80

this case shown as three, of locking buttons —10— having spaced headed ends between which the edges of toggle plates —8— and —9— are loosely positioned. The combined width of toggle plates —8— and —9— is greater than the normal distance between troughs —6— and —7— so that when the toggle plates —8— and —9— are moved into the same plane the spring plate —4— 85

will be bent outwardly against its own resiliency with the result that when the toggle plates —8— and —9— are moved beyond the same plane the action of spring plate —4— will cause the toggle plates to spring upwardly or downwardly as the case may be and will yieldingly hold them in such 90

position. The extent of movement of toggle plates —8— and —9— upwardly is limited by the locking buttons —10— and the downward movement of toggle plates —8— and —9— is limited due to the fact that the opposing prongs 95

hereinafter to be described are caused to meet and lock together by such downward movement.

Toggle plate —8— is provided with a plurality, in this case shown as three, of slots 11—11 positioned in spaced relation longitudinally thereof and for a purpose hereinafter to be described. 100

Toggle plate —9— is provided with a plurality in this case shown as three, of similar slots 12—12 positioned in spaced relation longitudinally there- 105

of for a purpose hereinafter to be described.

I further provide a pair of prong carrying 110

plates —13— and —14—, prong carrying plate —13— being positioned to coact with toggle plate —8— and prong carrying plate —14— being positioned to coact with toggle plate —9—. The design of prong carrying plate —13— and its functioning with relation to toggle plate —8— is the same as the design of prong carrying plate —14— and its functioning with toggle plate —9— so that a description of one is a description of the other.

Prong carrying plate —13— carries a plurality, in this case shown as fifteen, of prongs or arcuate rods —15— affixed to the upper surface thereof in spaced relation by welding or other convenient means. The under surface of prong-carrying plate —13— is provided with a plurality, in this case shown as three, of depending headed rivets —16— which extend downwardly through slots —11—, the heads —17— of the rivets —16— being larger than the width of the slots —11— so that the prong carrying plate —13— and the toggle plate —8— are secured together but may be moved relatively to each other inasmuch as the rivets —16— are a sliding fit in slots —11—.

For the purpose of manually controlling the movement of prong carrying plate —13— with relation to toggle plate —8— I provide a bell-crank —18— pivotally mounted on the under surface of toggle plate —8— adjacent one end thereof by means of pivot pin —19—. A link —20— is pivotally mounted to one arm of bell-crank —18— and has its other end pivotally connected to a rivet —21— which is affixed in the under surface of prong-carrying plate —13— extending downwardly through a slot, not shown, but which is similar to slot —22— shown in toggle plate —9—.

On the upper surface of prong carrying plate —13— I provide a plurality, in this case shown as four, of spring clips —23— affixed to the upper surface thereof by rivets —24— or other convenient means. Spring clips —23— extend outwardly beyond the longitudinal edges of prong carrying plate —13— and are fashioned with upwardly and inwardly turned ends as —25— and —26—.

I further provide a cover plate —27— having a plurality of holes —28— for the reception of prongs —15— and having its longitudinal edges inturned so that they may be placed over the in-turned edges —25— and —26— of clips —23— to hold cover plate —27— in position through the resilient action of clips —23—.

It will be understood that the second prong-carrying plate —14— is similarly constructed carrying a plurality of prongs —29— and spring clips —30— and is provided with a cover plate —31—. Prong-carrying plate —14— is secured in place on toggle plate —9— by a plurality of headed rivets —32— extending through slots 12 in the latter and carries at one end a bell-crank —33— and link, not shown, which is similar in construction and function to the bell crank —18— hitherto described. Bell-crank —33— is positioned at one end of book back —3— and bell-crank —18— is positioned at the other end of book back —3—.

The upper ends of prongs —15— are V-shaped as shown at 34 on Figure 2 and the upper ends of prongs —29— are fashioned with V-slots as shown at 35 in Figure 2 so that when toggle plates 8 and 9 are depressed beneath a normal plane the V-shaped ends 34 of prongs —15— will enter and register with the V-slots 35 of prongs —29— as shown in Figure 3.

When it is desired to place sheets on to or remove sheets from prongs —15— and —29— toggle plates 8 and 9 are raised above a normal plane thereby separating prongs —15— from prongs 29 as shown in Figure 4 and thus permitting the insertion or removal of the sheets.

In the normal position of the prong assembly the bell cranks —18— and —33— are in the position shown in Figure 7 with the opposite ends of prong-carrying plates —13— and —14— in the same plane and with the opposing prongs —15— and —29— in registration as shown in Figure 1.

When it is desired to move sheets either up and down in the book the sheets are first transferred to one set of the prongs, as for example prongs —15—, and toggle plates 8 and 9 are then raised above a normal plane so that prongs —15— are separated from prongs —29—. Bell-crank —18— is then rotated about its pivot —19— thereby causing link —20— to move outwardly towards the end of the book which will cause prong carrying plate —13— to move longitudinally with respect to toggle plate 8 to and beyond the end of the book. Similarly bell-crank —33— is rotated about its pivot causing prong-carrying plate —14— to move longitudinally of toggle plate 9 to and beyond the end of the book. The result of the longitudinal movement in opposite directions of prong-carrying plates —13— and —14—, as just described, will place prongs —15— and prongs —29— in the relative position shown in Figure 2 so that the two prongs on the outer ends of both prong-carrying plates —13— and —14— will not be in a position to register with opposing prongs while the remaining prongs —15— will be in a position to register with prongs —29— second from the ones with which they would register in the normal position.

The toggle plates —8— and —9— are then depressed below a normal plane to bring prongs —15— and prongs —29— together, the sheets are then moved from prongs —15— onto prongs —29—. Prongs —15— and —29— are then opened as before described, bell cranks —18— and —33— are rotated about their pivots to the normal position which will result in the longitudinal movement of prong carrying plates —13— and —14— in a direction opposite to that just described and will return them to the normal position as shown in Figure 1. The prongs —15— and —29— will then be brought together into the normal position shown in Figure 1. The sheets will then be found to have been moved up or down in the book a distance of two prongs.

It will be understood that if it is desired to move the sheets in one direction the operation will be started with the sheets initially on prongs —15—, while if it is desired to move the sheets in the opposite direction the movement will be started with the sheets initially on prongs —29—. It will also be understood that if it is desired to transfer the sheets in either direction only one set of prongs then in that case only one of the bell cranks —18— or —33— will be rotated which will result in placing the prongs —15— and —29— in such a position with relation to each other that when they are then brought together a prong —15— will register with a prong —29— adjacent the prong —29— with which it would be normally in registration.

It will be understood that the size and relation of parts is such that the rotation of bell-crank —18— or bell-crank —33— will cause a

movement of the prong-carrying plate to which it is connected a distance just sufficient so that prongs —15— will be in a position to register with prongs —29—. It will also be understood that my device may be so constructed that the movements of prong-carrying plates —13— and —14— will be sufficiently great so that sheets may be transferred three or more sets of prongs if desired. It will also be understood that the materials of which my device are constructed and the exact method of assembling the different parts may be varied without departing from the spirit of my invention for although I have shown and described a specific structure and form of part as an exemplification of an embodiment of my invention I do not desire to restrict myself to the exact shape, form or relation of parts as various changes may be made within the scope of the appended claims.

20 I claim:

1. In a device of the class described, a pair of opposed covers, a book back connecting the covers, a spring back plate secured to the book back, a pair of toggle plates operatively positioned in the spring back plate, a pair of prong-carrying plates, means for slidably securing a prong-carrying plate on the upper surface of each toggle plate, a plurality of prongs positioned on the upper surface of each of the prong-carrying plates in longitudinal spaced relation, a bell-crank pivoted to the under surface of one of the toggle plates, and a link having one end pivotally connected to one arm of the bell-crank and having its other end pivotally connected to the under surface of a prong-carrying plate whereby the rotation of the bell-crank will cause the prong-carrying plate to move longitudinally in relation to the toggle plate.

2. In a device of the class described, a pair of opposed covers, a book back connecting the covers, a spring back plate secured to the book back, a pair of toggle plates operatively positioned in the spring back plate, a pair of prong-carrying plates, means for slidably securing a prong-carrying plate on the upper surface of each toggle plate, such means limiting the movement of the prong-carrying plate in relation to the toggle plate on which it is carried, a plurality of prongs positioned on the upper surface of each of the prong-carrying plates in longitudinal spaced relation, a bell-crank pivoted to the under surface of one of the toggle plates, a link having one end pivotally connected to one arm of the bell-crank and having its other end pivotally connected to the under surface of a prong-carrying plate whereby the rotation of the bell-crank will cause the prong-carrying plate to move longitudinally in relation to the toggle plate.

3. In a device of the class described, a pair of opposed covers, a book back connecting the covers, a spring back plate secured to the book back, a pair of toggle plates operatively positioned in the spring back plate, a prong-carrying plate positioned on the upper surface of each of the toggle plates, a plurality of prong members positioned on the upper surface of each of the prong-carrying plates in longitudinal spaced relation, means for securing the prong-carrying plates on the toggle plates for permitting longitudinal movement of the prong-carrying plates in relation to the toggle plates, and a toggle joint connecting the end of a toggle plate with the corresponding end of the prong-carrying plate carried thereby, means for moving the toggle joints whereby a prong-carrying plate will be moved

longitudinally in relation to the toggle plate upon which it is positioned.

4. In a device of the class described, a pair of opposed covers, a book back connecting the covers, a spring back plate secured to the book back, a pair of toggle plates operatively positioned in the spring back plate, a prong carrying plate positioned on the upper surface of each of the toggle plates, a plurality of prong members positioned on the upper surface of each of the prong-carrying plates in longitudinal spaced relation, means for securing the prong-carrying plates on the toggle plates for permitting longitudinal movement of the prong-carrying plates in relation to the toggle plates said means limiting the movement of a prong-carrying plate in relation to the toggle plate on which it is carried, a toggle joint connecting the end of a toggle plate with the corresponding end of the prong-carrying plate carried thereby, means for moving the toggle joints whereby a prong-carrying plate will be moved longitudinally in relation to the toggle plate upon which it is positioned.

5. In a device of the class described, a pair of opposed covers, a book back connecting the covers, a pair of toggle plates operatively secured to the book back, a prong-carrying plate positioned on the upper surface of each of the toggle plates, means securing the prong-carrying plates on the upper surface of the toggle plates for permitting longitudinal movement of the prong-carrying plates in relation to the toggle plates, bell-cranks pivotally mounted on the under surface of the toggle plates, and links pivotally mounted on one of the ends of the bell-cranks and having their other ends pivotally connected to the under surface of a prong-carrying plate whereby movement of the bell-cranks will cause the longitudinal movement of the prong-carrying plates in relation to the toggle plates.

6. A binder comprising toggle plates, means retaining the toggle plates in operative association and including a spring member yieldably retaining the toggle plates in either of two positions with their inner adjacent marginal edges above or below an imaginary horizontal line traversing their outer marginal edges, a ring section plate, half ring sections secured thereto, means for slidably connecting the plate to one of the toggle plates, a cover plate having openings through which said half ring sections extend near their lower ends and providing a smooth surface for the sliding movement of the leaves thereon, and means for securing the cover plate to the ring section plate.

7. A binder comprising toggle plates, means retaining the toggle plates in operative association and including a spring member yieldably retaining the toggle plates in either of two positions with their inner adjacent marginal edges above or below an imaginary horizontal line traversing their outer marginal edges, a ring section plate, half ring sections secured thereto, means for slidably connecting the plate to one of the toggle plates, a cover plate having openings through which said half ring sections extend near their lower ends and providing a smooth surface for the sliding movement of the leaves thereon, means for securing the cover plate to the ring section plate, and means including a rocking member exposed at one end of the binder for sliding said ring section plate lengthwise of the toggle plate.

8. In a visible record removable leaf holder, the combination of a back having tilting sections

therein, arranged to tilt about parallel axes disposed at the outer longitudinal edges of the back, ring halves on each section, instrumentalities whereby the ring halves on one section are movable in unison out of alignment with the ring halves of the other section, and means including a rocking member exposed at one end of the binder for effecting such movement.

9. In a visible record removable leaf binder, the combination of a back having tilting sections thereon arranged to tilt about parallel axes disposed at the outer longitudinal edges of the back, ring halves on each section, and instrumentalities for moving the ring halves on either section in

unison out of alignment with the ring halves of the other section.

10. In a visible record removable leaf binder, the combination of a back having tilting sections thereon arranged to tilt about parallel axes disposed at the outer longitudinal edges of the back, ring halves on each section, instrumentalities whereby the ring halves on either section are movable in unison out of alignment with the ring halves of the other section, and separate means, each including a rocking member for effecting such movement of the ring halves on respective sections.
